(57) **CLAIM**

The ornamental design for a display with support bracket, as shown and described.

DESCRIPTION

FIG. 1 is a rearward perspective view of a display with support bracket;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view of the “display with support bracket”, which is in a first state of use; and,

FIG. 9 is a perspective view of the “display with support bracket”, which is in a second state of use.

The broken lines in the drawings are employed to show unclaimed portions of the display with support bracket, and form no part of the claimed design.
